UNITED STATES PATENT OFFICE.

WARNER R. BUXTON, OF SPRINGFIELD, MASSACHUSETTS.

COLLAR-CONTAINER.

1,159,743.

Specification of Letters Patent.

Patented Nov. 9, 1915.

Application filed April 30, 1914. Serial No. 835,427.

To all whom it may concern:

Be it known that I, WARNER R. BUXTON, a citizen of the United States of America, residing at Springfield, in the county of ⁶ Hampden and State of Massachusetts, have invented new and useful Improvements in Collar-Containers, of which the following is a specification.

This invention relates to containers for ¹⁰ collars, cuffs, and like articles. It is designed more particularly to take the place of the well-known collar bag used when traveling.

An object of the invention is to provide ¹⁵ a container for collars and similar articles which may be readily shaped by the user to the desired form and size for the number of collars to be carried.

Another object of the invention is to provide ²⁰ in such a container for collars, a stiffening or reinforcing belt to preserve the shape of the collars and act as a protective member therefor.

Another object of the invention is to provide ²⁵ a collar retainer which, when not in use, can be rolled into compact form thereby occupying a minimum amount of space.

Another object of the invention is to combine in a collar container, a device whereby ³⁰ ties may be conveniently carried and kept pressed by the coöperation with parts of the collar container.

In general my device comprises a flat ³⁵ flexible member provided at its central zone with a stiffening strip. This member is designed to be adjusted to the desired circular size by means of the snap buttons at each side, one end closed by the draw-string, the collars inserted, and then the other end ⁴⁰ closed by its draw-string, thus forming a most compact article for traveling. On the interior of the flexible member, I preferably provide a compartment for scarfs or ties, which comprises flaps foldable in overlapping ⁴⁵ relation over the ties, thereby keeping them in shape and free from dust.

In the one embodiment of my invention, which I have chosen to illustrate in the accompanying drawings: Figure 1 is a developed view of the interior of my container; ⁵⁰ Fig. 2 is a developed view of the exterior thereof; Fig. 3 is a transverse sectional view taken on the line 3—3 of Fig. 2 and looking in the direction of the arrows; Fig. 4 is a view on a reduced scale showing the container hung upon the wall to display the

ties; Fig. 5 is a view showing the container wrapped around a number of collars and ready for packing or transportation.

Referring to the drawings, 1 is a flat strip ⁶⁰ of flexible material, such as leather, for example, which is cut to the shape shown in Figs. 1 and 2. Fastened to the strip 1 by any suitable means is a stiffening piece ⁶⁵ 5 preferably slightly greater in width than the height of a collar. This piece is applied to the member 1 at the central zone thereof and forms an adequate protective belt for the collars. The strip 1 and stiffening piece ⁷⁰ 5 are covered by a lining strip 2 of silk or other material which adds to the attractiveness of the container. Fastened to the flexible member 1 and the stiffening piece 5 near one end thereof are several pairs of male portions of spring or snap buttons 7, each ⁷⁵ pair distanced from the other in a longitudinal direction. At the other end of the container are fastened a pair of female portions of snap buttons 6 which are adapted to engage with any pair of the buttons 7. ⁸⁰

The flexible strip 1 is in effect a wrapper reinforced for stiffening and protective purposes by the member 5. This wrapper is preferably rolled into the shape shown in Fig. 5 and held by the buttons 6 and 7. ⁸⁵ Thus a container of the desired diameter is formed with tubular extensions on each side thereof. Near each side edge of the flexible wrapper 1 are the draw-strings 3 and 4. The latter are threaded in and out ⁹⁰ through holes in the flexible wrapper 1 in a well-known way. These strings 3 and 4 do not, however, pass through the lining 2 but are concealed thereby, as shown in Fig. 1. By one of these draw-strings 3 or 4, one end ⁹⁵ of the container is closed, the collars inserted, and then the other end is closed. The extensions may be held contracted or closed by tying the strings 3 and 4. On the outside of the bag, I preferably provide a pocket ¹⁰⁰ 13 to contain buttons, studs, and the like.

A tie compartment is preferably formed on the interior of the flexible strip 1 by the wings or flaps 9 and 10. These flaps 9 and 10 are fastened to member 1 adjacent ¹⁰⁵ the sides of member 5, and are adapted to be folded in overlapping relation and secured by snap buttons 11. Inside the flaps 9 and 10 and fastened to the protective strip 5 near one end thereof is a flexible strip ¹¹⁰ 12. This strip 12 is fastened at its middle portion, and the ends thereof may be held

by a snap button to form a loop through which the ties may be passed.

When the container is open, it may be hung from the wall by the ring 8 which is secured to the flexible member 1 in any suitable manner. When the device is thus used to display the neckwear, the loop 12 forms a support for the ties. By this structure and arrangement, the ties may be protected by the collar bag when carrying collars and rendered easily accessible at all times.

Thus, I have provided a collar bag or the like of an improved kind adjustable to the desired size and arranged when not in use to take a "condensed" form.

It is understood that many changes and modifications may be made to my device without departing from the scope of my invention which is more truly defined in the appended claims.

What I claim is—

1. A container for collars and the like, comprising in combination, a flexible wrapper, a longitudinal stiffening member therefor, flaps on the interior of said wrapper, arranged to be folded in overlapping relation over a number of neckties and to be backed up by said stiffening member, said wrapper adapted to be rolled longitudinally into a container of desired diameter for a number of collars leaving tubular end extensions on each end thereof, devices to fasten the ends of the wrapper in overlapping relation, said devices being arranged to permit adjustment of the diameter of the container as desired, together with means to contract and hold the top and bottom ends of said tubular extensions, as desired.

42. 2. A container for collars and the like, comprising in combination, a flexible wrap-

per, a longitudinal stiffening member therefor, flaps on the interior of said wrapper, a loop on the interior of said wrapper through which a number of ties may be passed, said flaps adapted to be folded in overlapping relation over the ties and to be backed up by the stiffening member, said wrapper adapted to be rolled longitudinally into a container of desired diameter for a number of collars leaving tubular end extensions on each end thereof, devices to fasten the ends of the wrapper in overlapping relation, said devices being arranged to permit adjustment of the diameter of the container as desired, together with means to contract and hold the ends of said tubular extensions.

3. A container for collars and the like, comprising in combination a flexible wrapper, a longitudinal stiffening member therefor, flaps on the interior of said wrapper, a loop on the interior of said wrapper through which a number of ties may be passed, said flaps adapted to be folded in overlapping relation over the ties, and to be backed up by the stiffening member, means to support the wrapper in an unwrapped condition from a wall to display said ties, said wrapper adapted to be rolled into a container of desired diameter for a number of collars leaving tubular end extensions on each end thereof, devices to fasten the ends of the wrapper in overlapping relation, said devices being arranged to permit adjustment of the diameter of the container as desired, together with means to contract and hold the ends of said tubular extensions.

WARNER R. BUXTON.
